UNITED STATES PATENT OFFICE.

WILLIAM L. MAFFETT AND JAMES C. GRAY, OF TRION, GEORGIA, ASSIGNOR OF ONE-
THIRD TO JOHN C. MATTHEWS, OF TRION, GEORGIA.

LOOM LET-OFF MECHANISM.

1,358,088.

Specification of Letters Patent.

Patented Nov. 9, 1920.

Application filed October 17, 1919. Serial No. 331,391.

To all whom it may concern:

Be it known that we, WILLIAM L. MAFFETT and JAMES C. GRAY, citizens of the United States, residing at Trion, in the county of Chattooga and State of Georgia, have invented certain new and useful Improvements in Loom Let-Off Mechanism, of which the following is a specification, reference being had therein to the accompanying drawings.

This invention relates to an improved let-off mechanism for looms, and contemplates more particularly a device for use in connection with the well known Bartlett or similar type of let-off.

In practice at the present time, certain difficulties are experienced with the known let-off mechanisms, in which the warp beam cannot be let back without manipulating and releasing some of the mechanical elements, and without the usual oily and soiling consequences. Numerous attempts have been made to overcome these disadvantages, but in each instance the mechanism produced is complicated and dependent upon the manipulation of at least certain parts of the device.

It is the primary object of the present invention to produce a device the use of which will permit the warp beam to be grasped and let back by an operative without the necessity of operating or releasing any of the mechanical parts of the let-off mechanism.

Another object of the invention is the production of a let-off device in which an automatic and yieldingly acting clutch is provided for normally controlling the operation of the mechanism, and at the same time permit of a reverse movement when the loom is stopped and the warp beam is grasped by an operative and moved the required distance.

With these and other objects in view the invention further consists in the construction and arrangement of the several parts hereinafter described and pointed out in the appended claims.

In the drawings which show by way of illustration an embodiment of our invention, and in which corresponding reference characters designate similar parts,

Figure 1 is a view in side elevation of a let-off mechanism as applied to a loom;

Fig. 2 is an end elevation;

Fig. 3 is an enlarged horizontal sectional view partly in elevation, on the line 3-3 of Fig. 2, showing the manner in which the device is attached to the frame of the loom;

Fig. 4 is an enlarged detail horizontal sectional view through the clutch when engaged; and

Fig. 5 is a similar detail view showing the ratchet part of the clutch disengaged when the beam is let back.

The present invention has been primarily designed for use in connection with the Bartlett let-off mechanism and comprises a novel clutch having an intermediate movable member arranged to co-operate with mating members, one of said mating members being keyed to the shaft, and the other of said members being loosely mounted thereon.

Referring to the drawings, a conventional form of Bartlett let-off mechanism is shown, attached to a portion of the frame 1 of a loom. Brackets 2 support and form bearings for the shaft 3 of the let off mechanism; and are secured in any preferred manner to the frame 1 of the loom.

The usual pawl and ratchet mechanism 4 is shown positioned on the shaft 3, and is interconnected with the link 5 which in turn is attached to the lay from which it receives motion. The brake or friction device 6 is positioned at the top of the shaft 3, and the worm is indicated at 7. The foregoing elements form of themselves no part of the present invention except as used in conjunction with the novel form of clutch to be presently described. The arrangement of shaft 3 and worm 7 permits the work beam to rotate as will be understood.

Meshing with the worm 7 is a worm gear 8 keyed to one end of a power transmitting shaft 9. The shaft 9 is supported in a bearing 10 formed in the bracket 11 secured to the frame of the loom, as best shown in Fig. 3. Arms 12 extend from the bracket 11 and are each provided with slots 13 through which bolts 14 pass for adjustably securing the bracket to the frame as will be understood.

Upon the opposite end of the shaft 9 is loosely mounted a gear 15 arranged to mesh with the gear 16 carried by the usual warp beam 17. The gear 15 is preferably detachably positioned upon the shaft 9 by means of a cotter pin and washer 18 as shown, or any other approved device may be used as will be understood. The gear 15 is provided

on one face thereof with one member 19 of the clutch mechanism now to be described.

This clutch member 19 is in the form of a ratchet and is arranged to normally engage 5 a mating member 20 carried by the intermediate and movable clutch element 21. A reduced hub section 22 of the clutch element 21 bears against the face of the gear 15 when the clutch is engaged and the loom is 10 operating, thereby insuring a positive and durable engagement of the clutch members 19 and 20. The hub section 22 also serves to guide the intermediate clutch element 21 when moved upon the shaft 9 during the disengagement of the clutch members 19 and 20.

The intermediate clutch element is slidably mounted upon the power transmitting shaft 9, and in addition to the clutch member 20, is also provided with protruding lugs 20 23 forming a clutch member 24 as shown. Associated with the protruding lugs 23 are other lugs 25 forming a clutch member 26. The lugs 25 are carried by an annular collar 27 fixedly keyed to the shaft 9 as best shown 25 in Fig. 4. A spring 28 is interposed between the intermediate movable clutch element 21 and the aforesaid fixed collar 27. The spring is arranged to surround the several lugs forming the clutch members 24 and 26, and normally force the movable clutch element 21 and more particularly the clutch member 19 thereof into engagement with the clutch member 20 carried by the gear 15.

In letting back the warp beam it will be 30 seen that the clutch member 20 will ride out of engagement with the clutch member 19 as shown in Fig. 5. This disengagement of the clutch does not require any releasing or manipulating of the let-off mechanism. The 35 warp beam is conveniently grasped by an operative at the place where he is standing and turned back, and as a result the operative is not compelled to soil his hands with oil and grease, as is now the case. At present the oil and grease from an operative's hands 40 as the result of manipulating the let-off mechanism, are often worked into the material produced causing either the material to be wasted or reduced to an inferior quality and value.

The construction of the clutch mechanism permits of a positive normal engagement during the operating of the loom, and its easy disengagement when being let back.

55 As a result, the invention has been found to greatly reduce the time now lost by operatives in walking about the loom when manipulating the present forms of let-off mechanisms.

60 Various changes in the size, proportion and arrangement of the several parts herein described may be made without departing from the invention and we do not limit ourselves to the exact construction set forth 55 herein.

We claim:

1. In a let-off mechanism for looms, the combination with a work beam provided with a gear, of transmitting means including a shaft for permitting the rotation of 75 said work beam, a gear loosely carried by said shaft and adapted to mesh with the gear provided on the work beam, means for operating said transmitting means, and a clutch provided between the said shaft and the aforesaid loosely mounted gear for transmitting movement to the work beam when moving in one direction, said clutch permitting the work beam to be moved back when said beam is moved in the opposite 80 direction without effecting any change of the mechanism of the loom.

2. In a let-off mechanism for looms, the combination with a work beam, of transmitting means for permitting the rotation 85 of said work beam, means for operating said transmitting means for normally permitting the aforesaid rotation of the work beam, and means for automatically disengaging the aforesaid transmitting means 90 from the operating means when letting back the work beam.

3. In a let-off mechanism for looms, the combination with a warp beam provided 95 with a gear, of transmitting means including a shaft for permitting the rotation of said work beam, a gear loosely carried by said shaft and adapted to mesh with the gear provided on the warp beam, means for operating the aforesaid transmitting 100 shaft, and a clutch including a collar and a yieldable spring provided between said collar and the aforesaid loosely mounted gear, said clutch being engaged by said spring for permitting the rotation of the 105 warp beam when moved in one direction and disengaged by a reverse movement of the warp beam.

4. In a let-off mechanism for looms, the combination with a warp beam provided 110 with a gear, of transmitting means including a shaft for permitting the rotation of said work beam, a gear loosely carried by said shaft and adapted to mesh with the gear provided on the warp beam, means for 115 operating said power transmitting shaft, a clutch including a relatively fixed collar secured to the aforesaid shaft, a spring interposed between said collar and the aforesaid loosely mounted gear for normally engaging the clutch and means for disengaging the clutch when the warp beam is moved back.

5. In a let-off mechanism for looms, the combination with a warp beam provided 125 with a gear, of transmitting means including a shaft for permitting the rotation of said work beam, a gear loosely carried by said shaft and adapted to mesh with the gear provided on the warp beam, means for 130

operating the aforesaid shaft, a clutch including a relatively fixed collar secured to said shaft and having lugs extending therefrom, a movable clutch element provided 5 with mating lugs adapted to engage the aforesaid lugs, a spring interposed between the said collar and the aforesaid loosely mounted gear, for normally engaging the clutch, and means including mating clutch 10 members provided on the said movable clutch element and the loosely mounted gear, respectively, whereby the clutch is automatically disengaged upon the reversal of the warp beam.

15 6. In a let-off mechanism for looms, the

combination with a warp beam provided with a gear, of transmitting means including a shaft for permitting the rotation of the work beam, a gear loosely carried by said shaft and adapted to mesh with the 20 gear provided on the warp beam, means for operating said shaft, a clutch for normally transmitting movement from the power transmitting shaft to the warp beam and means for automatically disengaging 25 the clutch when letting back the warp beam.

In testimony whereof we affix our signatures.

WILLIAM L. MAFFETT.

JAMES C. GRAY.
